ELECTRIC VALVE CONVERTING SYSTEM

Renato Lombardi, Milan, Italy, assignor to General Electric Company, a corporation of New York

Application June 26, 1934, Serial No. 732,448
In Italy August 9, 1933

13 Claims. (Cl. 175—363)

My invention relates to electric valve converting systems, and more particularly to such systems including electric valves for transmitting energy between direct and alternating current circuits.

Heretofore, there have been devised numerous apparatus including electric valves for transmitting energy between direct and alternating current circuits, wherein rectifiers or inverters have been used to permit energy flow in one direction between the two systems. Furthermore, it is well known in the art that the direction of energy flow between the two systems may be reversed by reversing the connection of the electric valve apparatus on the direct current side. Generally, however, this has necessitated the interruption of the connection between the two systems for the purpose of reversal of the operation of the valve apparatus and this necessarily interrupts the continuity between the two systems. Such arrangements have been proposed for use on direct current traction systems or locomotives in which it was desired to apply the well known scheme of regenerative braking. In some instances these locomotives have been equipped with direct current motors and the alternating current received from the trolley was rectified by the apparatus carried by the locomotive. In other systems, however, alternating current feeder systems have supplied converting apparatus which fed the direct current trolley system. It will be apparent that where regenerative braking is used in such traction systems there will be a reversal of the flow of energy between the two current systems. Obviously, of course one of the chief disadvantages of the prior arrangements has been that there has been a discontinuity between the two current systems whenever the electric valve apparatus was reversed in operation, and that often reversal of such apparatus occurred at the improper time.

It is an object of my invention, therefore, to provide an improved electric valve converting system for transmitting energy between direct and alternating current circuits which will overcome the above mentioned disadvantages of the arrangements of the prior art, and which will be simple and reliable in operation.

It is another object of my invention to provide an improved electric valve system which will obtain an accurate and reliable indication of the conditions under which it is desired that the operation of the electric valve converter is to be reversed, and to avoid needless reversal of the electric valve converter connections.

It is a further object of my invention to provide an electric valve converting system wherein the connections of the inverting apparatus may be reversed without interrupting the electrical continuity between the alternating current and the direct current systems.

In accordance with my invention, the direct and alternating current circuits are interconnected through a pair of electric valve converting apparatus which may be of any of the several types well known in the art, although I prefer to use apparatus of the grid controlled electric valve type. One of these electric valve converting apparatus is connected between the two current systems so as to operate in a direction in which the predominant energy flow occurs, while the other electric valve apparatus, which may be of small capacity, is arranged to be connected in a manner so as to operate in a direction opposite to the first electric valve apparatus and to be connected between the two systems during the time that the reversal of the connections to the first apparatus occur. Thus, at all times, there is a continuity between the two current systems. Furthermore, in accordance with my invention, there is provided a device for detecting the conditions under which the automatic conversion of the direction of power transmission between the two networks becomes necessary. This detection device prepares the circuit and does the actual reversal of the connection to the main electric valve converter.

For a better understanding of my invention, together with other and further objects thereof, reference may be had to the following description taken in connection with the accompanying drawing, in which Fig. 1 illustrates an embodiment of my invention for transmitting energy between a three-phase alternating current circuit and a direct current circuit, and Fig. 2 schematically shows the grid circuit excitation arrangement.

Referring to Fig. 1 of the drawing, there is illustrated a polyphase valve converting system for transmitting energy between the three-phase alternating current system 10 and a direct current system 11. A converter 12 of sufficient capacity to carry any load which may appear across the direct current lines 11 is connected between the direct current circuit and the alternating current circuit 10 by means of the direct current conductors 11 and the polyphase inductive networks 13 and 14.

While I have shown a multi-anode single-cathode vapor electric discharge device of the grid

controlled type, it will be apparent to those skilled in the art that other electric discharge devices may be utilized or that a plurality of electric valves each having an anode, a cathode and a grid element, may be used in place of the multi-anode single-cathode discharge device 12. An auxiliary electric discharge device 15 normally disconnected, is arranged between the direct current line 11 and the alternating current circuit 10 through the medium of the polyphase networks 16 and 17. This electric discharge device 15 is arranged so as to operate as an inverter when connected to the direct current line 11. The grid control circuits for the electric valve discharge devices 12 and 15 have not been shown in detail, inasmuch as the particular form or type of grid circuit forms no part of my invention and any suitable grid control circuits may be used, as is well understood by those skilled in the art.

In order to detect a condition precedent to a reversal of the normal direction of the flow of energy between the alternating current circuit 10 and the direct current circuit 11, an electroresponsive device 18 is arranged so as to have its energizing coil connected across a current shunt 19 in circuit 11'. As will be evident, the no load conditions appearing across the connections 11' will be an indication that there may be a possibility of a reversal of the direction of energy flow between the direct and alternating current circuits. The electroresponsive device, or relay 18, is normally energized so as to be in the position shown when there is a flow of energy from the alternating current circuit to the direct current circuit. A low voltage circuit 20, preferably alternating current in nature, supplies energy to the apparatus which will be actuated in response to a cessation of a reversal of the energy flow between the alternating and direct current circuits. Whenever the load across the rectifier 12 drops to zero the relay 18 becomes deenergized so that the armature drops to close its contacts 21 thereby closing a circuit which energizes a relay 22. The relay 22 when energized, closes a contact 23 which completes the circuit connection of the inverter 15 with the direct current circuit 11. The inverter 15 has a capacity which is of the order of but a few per cent of the normal capacity of the rectifier 12 and the grid excitation of the inverter 15 will be such that the voltage appearing across the direct current circuit 11, which, it will be remembered, is at a no load condition, can impress but a small current, as for example, .07 of 1% of the full load current of the rectifier 12, upon the alternating current circuit 10. If now, however, a reversal of the energy flow between the alternating and direct current circuits occurs, such as would be the case when a regenerative locomotive is across the direct current line 11, the voltage of the direct current circuit will increase so that the current inverted by the inverter 15 will also increase. A maximum demand relay 24 connected between the inverter 15 and one side of the direct current circuit 11, will be energized as soon as the current load of the inverter has reached a certain value, as for example, .5 of 1% of the full load current of the rectifier 12. The energization of the relay 24 closes its contacts 25 thereby completing a circuit which energizes an actuating coil 26, for operating a reversing switch 27 to one of its operating positions. This reversing switch is interposed between the direct current circuit 11 and the direct current leads 11' which are connected to the electric discharge device 12. Thus, when

the switch 27 has been actuated, the connections to the electric valve apparatus 12 have been reversed so that this apparatus may now operate as an inverter. It will be noted, however, that the actuation of the armature of the actuating coil 26 has caused its circuit to be interrupted by means of contacts 28, and that other contacts 29 and 33 are simultaneously closed. The contacts 29 control the energization of a holding coil 30 which maintains switch 27 in the new position. The circuits controlled by contacts 33 to 41 will be described hereinafter. Inasmuch as a regenerative locomotive or a reversal of the direction of normal energy flow between the alternating and direct current circuits has caused the actuation of the switch 27, it will be apparent that current is now flowing through the electric discharge device 12, which is operating as an inverter, and through the shunt 19. A current flow through the electric discharge device 12 which is now operating as an inverter, also produces a flow of current through the actuating coil of the relay 18. As a result of this, the armature of the relay 18 is drawn into its illustrated position and its contacts 21 which control the energization of the actuating coil of the relay 22 have been separated, so that the armature of this relay now drops to open its contacts 23. This opening of the contacts 23 disconnects the inverter 15 from the line and also permits the relay 24 to return to its deenergized position.

If at a subsequent time this regenerative condition ceases so that the direct current circuit 11 is at a no load condition, current will no longer be flowing through the shunt 19 and through the actuating coil of the relay 18, with the result that the armature of this relay will now drop, thereby closing the contacts 31 which are connected in series relation with the previously mentioned closed contacts 33 of relay 26 to control the energization of the coil of a second relay 32 for operating switch 27. Relay 32 is of the time delay type which will operate only after a predetermined time interval. When this time interval has been completed, the relay 32 will operate to restore the switch 27 to its original position. In doing so, however, the contacts 33 which are in series with the circuit of the energizing coil of the relay 32 are opened thereby interrupting the operating circuit of relay 32. At the same time, however, a set of contacts 34 operated by relay 32 are closed. These contacts are in the circuit of a holding coil 35, which maintains the switch 27 in its restored position. The time delay relay 32 operates to prevent needless reversal of the switch 27 in case the regenerative condition of the lines 11 is momentarily interrupted.

It will be apparent from the description of the apparatus that at the time when the regenerative condition has ceased to exist so that the relay 18 has become deenergized thereby closing contacts 31, it has also closed contacts 21, which in turn again connects the inverter 15 across the line 11 by means of the circuit previously described, so that during the time interval necessary for the coil of the relay 32 to complete its operation the inverter 15 is connected across the direct current line. Hence, during the time of restoration of the switch 27 to its original position the continuity of interconnection of the apparatus between the direct and alternating current lines has been maintained.

In Fig. 2 there is disclosed diagrammatically the grid circuit arrangement which is controlled

5 by the switch contacts 36 to 41 as the main switch mechanism is operated in Fig. 1. The right-hand contacts of each of the pairs of contacts 36 to 41 are connected to the alternating current line 10. The left-hand contacts of the pairs of contacts 36, 38 and 40 are connected to a phase shifter indicated by the rectangle 42. The left-hand contacts of the pairs of contacts 37, 39 and 41 are connected to a phase shifter indicated by the rectangle 43. The phase shifters 42 and 43 are connected to the primary windings of the group of grid circuit transformers indicated by the rectangle 44. The secondary windings of the grid circuit transformers indicated by the rectangle 44 are connected respectively to the cathode and the grids of the rectifier device 12.

10 In Fig. 1 a phase shifter is denoted by the rectangle 45 and this is connected to energize the primary windings of the group of grid circuit 15 transformers indicated by the rectangle 46. The secondary windings of the grid circuit transformers indicated by the rectangle 46 are connected, respectively, to the cathode and to the grids of the rectifier device 15. As will be apparent to those 20 skilled in the art, the phase shifters denoted by the rectangles 42, 43 and 45 may be any of the phase shifting circuits or devices well known in the art and the grid circuit transformers utilized in the rectangles 44 and 46 may be of the type 25 which produce peaked wave form so as to supply a sharp impulse of short duration. Obviously, of course, the grid circuit may include a source of biasing voltage and the customary current limiting resistors.

30 35 While in the above arrangement, inverter 15 has been connected so as to be normally disconnected from the direct current line during the time that the electric discharge device 12 is connected to the direct current circuit, it will be apparent to one skilled in the art, however, that complete continuity of interconnection between the direct and alternating current circuits may also be obtained by connecting the inverter 15 so that it will be connected continuously across the 40 direct current circuit. This will be accomplished by omitting the following elements which include the contacts 21 of the relay 18, the relay 22 and its contacts 23. The relay 24, however, will operate in its usual manner so that at no load conditions the relay 24 will remain deenergized, but whenever a regenerative condition occurs across the line 11 this relay will pick up so as to energize the coil of the actuating relay 26 which controls the actuation of the reversing switch 27.

45 50 While I have shown and described my invention in connection with certain specific embodiments, it will, of course, be understood that I do not wish to be limited thereto, since it is apparent that the principles herein disclosed are susceptible of numerous other applications, and modifications may be made in the circuit arrangement and in the instrumentalities employed without departing from the spirit and scope of my invention as set forth in the appended claims.

55 60 What I claim as new and desire to secure by Letters Patent of the United States, is:

65 70 1. The combination in an electric energy converting system of a direct current circuit, an alternating current circuit, a converter interconnecting said circuits for transmitting energy normally in one direction between said circuits, an auxiliary converter for transmitting energy between said circuits in a direction opposite to that of said first converter, means cooperating with said auxiliary converter for detecting a condition prece-

75 dent to a reversal of the direction of any energy flow between said circuits, and means responsive to said first means for maintaining continuity of interconnection between said circuits and for reversing the direction of operation of said first converter.

80 85 90 2. An electric energy converting system comprising a direct current circuit, an alternating current circuit, an electric valve converter interconnecting said circuits for transmitting energy normally in one direction between said circuits, an auxiliary electric valve converter for transmitting energy between said circuits in a direction opposite to that of said first converter, means cooperating with said auxiliary converter for detecting a reversal of the direction of the normal energy flow between said circuits, and means actuated by said first means for reversing the direction of operation of said first converter.

said auxiliary converter to said circuits, means responsive to energy flow in an opposite direction between said circuits for reversing said connections of said first converter, and means responsive to a subsequent cessation of energy flow between said circuits for restoring said converting system to the original condition.

7. An electric energy converting system comprising an alternating current circuit, a direct current circuit, a converter having connections with said circuits for transmission of energy normally in one direction between said circuits, a small auxiliary converter arranged for interconnecting said circuits for transmission of energy in the opposite direction, means responsive to a cessation of a flow of energy through said first converter for connecting said auxiliary converter to said circuits, means responsive to a predetermined energy flow through said auxiliary converter for reversing said connections of said first converter for transmitting energy in the opposite direction, and means responsive to subsequent cessation of energy flow through said first converter for restoring said connections to the original condition.

8. An electric energy converting system comprising an alternating current circuit, a direct current circuit, an electric valve converter interconnecting said circuits, an auxiliary electric valve converter for transmitting energy between said circuits in a direction opposite to the normal direction of energy flow through said first electric valve converter, means responsive to a predetermined energy flow through said auxiliary converter for reversing the direction of energy flow through said first electric valve converter, and means responsive to a cessation of energy flow through said first electric valve converter for restoring said first valve converter to said original operating condition.

9. An electric energy converting system comprising an alternating current circuit, a direct current circuit, an electric valve converter interconnecting said circuits, an auxiliary converter for transmitting energy between said circuits in a direction opposite to the normal direction of energy flow through said electric valve converter, means responsive to a predetermined energy flow through said auxiliary converter for reversing the direction of energy flow through said electric valve converter, and means responsive to a cessation of energy flow through said electric valve converter for restoring said valve converter to said original operating condition after a predetermined time interval.

10. An electric energy converting system comprising an alternating current circuit, a direct current circuit, an electric valve converter interconnecting said circuits, an auxiliary converter normally disconnected and arranged for transmitting energy between said circuits in a direction opposite to the normal direction of energy

flow through said electric valve converter, means responsive to a predetermined minimum energy flow through said valve converter for connecting said auxiliary converter to said circuits, and means responsive to a predetermined energy flow through said auxiliary converter for reversing the direction of energy flow through said electric valve converter.

11. An electric energy converting system comprising an alternating current circuit, a direct current circuit, an electric valve converter interconnecting said circuits, an auxiliary converter normally disconnected and arranged for transmitting energy between said circuits in a direction opposite to the normal energy flow through said electric valve converter, means responsive to a predetermined minimum energy flow through said valve converter for connecting said auxiliary converter to said circuits, means responsive to a predetermined energy flow through said auxiliary converter for reversing the direction of energy flow through said electric valve converter, and means responsive to a cessation of energy flow through said valve converter for restoring said valve converter to the original condition after a predetermined time interval.

12. An electric energy converting system comprising an alternating current circuit, a direct current circuit, an electric valve converting apparatus interconnecting said circuits normally transmitting energy from said alternating current circuit to said direct current circuit, an auxiliary converting apparatus interconnecting said circuits for transmitting energy from said direct current circuit to said alternating current circuit, means connected between said auxiliary converting apparatus and said direct current circuit for reversing the operation of said valve converting apparatus in response to a predetermined energy flow through said auxiliary converting apparatus, and means responsive to a cessation of energy flow through said electric valve converting apparatus for restoring said valve converting apparatus to said normal operating condition after a predetermined time interval.

13. A reversible electrical conversion system for transmitting power in either direction without interruption at time of reversal, comprising two electric current lines, one of which is a direct-current line comprising at least two independent parallel connected converters, means associated with each of said converters for determining the operative condition thereof and relay means responsive to the electrical operating values of the direct-current line for controlling said means in sequence with said operating values so that upon reversal of current flow between said lines one of said converters is connected for reverse operation before the reversal of power flow.

RENATO LOMBARDI.
